UNITED STATES PATENT OFFICE.

THOMAS TUGBY, OF NIAGARA FALLS, NEW YORK.

DESIGN FOR A WATCH-CHARM.

SPECIFICATION forming part of Design No. 20,485, dated January 20, 1891.

Application filed November 1, 1890. Serial No. 370,084. Term of patent 7 years.

To all whom it may concern:

Be it known that I, THOMAS TUGBY, a citizen of the United States, residing at Niagara Falls, in the county of Niagara and State of New York, have invented and produced a new and original Design for Watch-Charms, of which the following is a specification.

Reference is to be had to the accompanying drawing, in which the figure represents in perspective a watch-charm embodying my new and original design.

The leading feature of my design consists in the lantern-shaped figure, the ornamental cap of which is convexed on its upper surface, the lines of the body of the cap departing in a downward direction from the top at a point inward from the edge of the same, and a series of vertically-ranging elliptical lines simulating guard-wires and departing from the body of the cap below the convexed top of the latter, and circular figures above the convexed cap. The cap of the representation B of the lantern-frame is convexed on the upper surface of its top b , and from the under side of

said top at a point inward from the edge the 25 lines of the body b' of the cap depart.

Between the body b' and the base B' appears a series of vertically-ranging elliptical lines b^2 , simulating guard-wires, said lines b^2 joining the band-like figure b^3 , representing 30 the upper part of the base. The lower defining-lines of the band-like figure b^3 join the concavo-convex bottom b^4 of the base, said concavo-convex form being indicated at b^5 .

Within the elliptical lines b^2 appears the 35 ellipsoidal figure C, representing a lantern-globe.

Above the convexed top b of the cap appear the interlocked circular figures or rings d d' . 40

I claim—

The design for a watch-charm herein shown and described.

THOMAS TUGBY.
